UNITED STATES PATENT OFFICE

2,378,013

SYNTHETIC MODULATOR SYSTEM

Richard A. Hiltferty, Baldwin, N. Y., assignor to
Press Wireless, Inc., Chicago, Ill., a corporation
of Delaware

Application September 18, 1943, Serial No. 502,870

6 Claims. (Cl. 250—17)

This invention relates to radio transmitter and receiver systems and more especially to systems where intelligence signals are represented by tone or audio frequencies.

A principal object of the invention is to provide a novel system of transmitting facsimile signals and the like without using expensive audio frequency modulating equipment at the transmitter.

One very well-known method of transmitting facsimile or similar signals by means of a radio transmission link, is to convert the shade values of the original subject matter into audio frequency tones which either directly or indirectly are used to amplitude-modulate a radio frequency carrier. Such a method requires expensive amplitude-modulating equipment at the transmitter for amplitude modulation of the carrier. Not only are such modulators expensive as regards initial cost and installation, but they are seldom used at their full frequency utilizing capacity because the audio frequency modulating band to be transmitted is usually very narrow, e. g., 1500-3000 C. P. S., as compared with the audio modulating equipment which is usually designed for operation between 50 and 10,000 C. P. S.

Accordingly, another object is to provide a system of transmitting different audio frequency tone signals by means of radio carriers without using conventional audio modulator equipment at the transmitter, while allowing reception to take place with conventional radio receivers of the amplitude-demodulation kind.

A feature of the invention relates to a flexible service radio system employing a pair of non-amplitude-modulated transmitters whose relative frequency difference is varied in a desired audio frequency manner; these transmitters can alternatively be used in the conventional manner as independent telegraph-keyed transmitters.

Another feature relates to the novel organization, arrangement and relative interconnection of parts which cooperate to produce a novel and flexible radio service system.

Other features and advantages not specifically enumerated will be apparent after a consideration of the following detailed descriptions and the appended claims. In the drawings,

Fig. 1 represents in schematic block diagram form, a radio transmitter and receiver system according to the invention.

Fig. 2 is a modification of Fig. 1.

Fig. 3 is another modification.

Referring to Fig. 1, the radio frequency excitation portion of the transmitter comprises two sep-

arates radio frequency oscillators 1 and 2, which may be of any well-known type, and if desired, provided with suitable amplifiers and buffers as well-known in the radio transmitter art. The frequency of oscillator 1 may be fixed for example at 15,639 kilocycles, while oscillator 2 is of a signal controlled shiftable frequency which can be shifted for example from 15,640 to 15,640.5 kilocycles. The oscillators are designed so that their actual frequency difference is equal to the range of audio tones which it is desired to transmit and reproduce at the receiver. For example, in the case of facsimile transmission, a suitable facsimile scanning arrangement 3 is provided whereby the shades of the original subject matter are converted into currents which, at the receiver, will appear as audio frequency tones for example 1000 to 1500 C. P. S. Thus the lowest current may represent "white" while the highest current may represent "black" or vice versa. If desired, although it is not necessary, the converter may be adjusted so that for the range of shades to be covered, the uppermost audio frequency tone or the uppermost portion of the 1000 to 1500 C. P. S. spectrum, is always less than the second harmonic of the lowermost tone and therefore less than the second harmonic of any tone or frequency in the said spectrum. For a detailed description of such an arrangement, reference may be had to Patent No. 2,299,937, the disclosure of which is herein incorporated by reference.

The two radio frequencies from oscillators 1 and 2 are fed to a common radio frequency transmitting amplifier 4 whose output is applied to a radiating antenna 5. Amplifier 4 should be of the distortionless type such as a class B amplifier. The two radio frequencies will therefore be radiated as two discrete frequencies. At the receiver terminal the two radiated frequencies are picked up by the receiving antenna 6 to which is connected an ordinary radio receiver of the amplitude-demodulation type. For illustrative purposes, a superheterodyne receiver is shown comprising the radio frequency amplifier section 7; the first detector or intermediate frequency converter section 8; the intermediate frequency amplifier section 9; the detector section 10 such as used in detecting amplitude modulation; and suitable audio frequency amplifier section (not shown). Assuming the original signals to be in the 1000-1500 C. P. S. band, the receiver is tuned to the mean frequency between the two radiated frequencies of 15,640 and 15,640.5 kilocycles. Under those conditions, when the variable oscillator rests at 15,640 kilocycles, the audio frequency out-

put of the receiver is 1000 C. P. S. When the variable oscillator is shifted to 15,640.5 kilocycles, the receiver output is 1500 C. P. S. This 1000 to 1500 C. P. S. signal can then be used to control the reproduction of the original facsimile shades in the well-known manner and as explained in said Patent No. 2,299,937.

Preferably, and as described in said patent, the output of the radio receiver may be passed through a band-pass filter having an effective band pass of 1000 to 1500 C. P. S., and it is then subjected to a level uniforming or limiting device to bring all the frequencies to the same amplitude. These uniform amplitude frequencies are then passed through a frequency discriminator and rectified to convert them into corresponding D. C. signals of variable amplitude which can then be applied to the facsimile re-converter 11.

As indicated in Fig. 2, instead of varying one radio frequency oscillator, both oscillators may be simultaneously varied under control of unit 3, in order to produce the desired audio frequency difference range. In this case, if a 500 C. P. S. shift is desired, each radio frequency oscillator need be shifted only 250 C. P. S.

As indicated in Fig. 3, instead of using a single transmitter to radiate the two radio frequencies from a single antenna, two entirely separate transmitters and antennae may be employed. With such an arrangement, class C amplifiers may be used to amplify the radio frequency carriers before application to the antenna. Whereas, in the case of Figs. 1 and 2, it may be necessary to use class B linear amplifiers which are more critical than class C amplifiers.

It will be understood that each transmitter in the system of Fig. 3, can be independently keyed for separate telegraph message transmission or the like when the simultaneous use for facsimile as above described, is not required.

Various changes and modifications can be made in the disclosed embodiments without departing from the spirit and scope of the invention.

What is claimed is:

1. The method of radio carrier transmission without the use of audio-frequency amplitude modulation of a carrier which comprises, generating two primary carriers, one of fixed frequency and the other of shiftable frequency, radiating said two separate radio frequency carriers, and shifting the frequency of said other primary carrier without audio-frequency amplitude modulation according to signals to be transmitted so

that the actual frequency difference between said primary carriers is equal to the frequency of the signal to be transmitted.

2. The method according to claim 1 in which the frequencies of both the radio frequency carriers are simultaneously varied so that the actual frequency difference equals the frequency of the signal to be transmitted.

3. The method of radio carrier transmission of signals represented by audio frequency tones within a predetermined band and without the use of audio-frequency modulation of the carrier which comprises, generating primary radio frequency oscillations, generating other primary radio frequency oscillations, shifting the frequency of said other oscillations without audio-frequency amplitude modulation so that the actual frequency difference with the first radio frequency oscillations equals the frequency of the tone to be transmitted, and radiating both said radio frequency oscillations from a common antenna.

4. The method of radio carrier transmission which comprises, generating a first primary radio frequency carrier, generating a second primary radio frequency carrier, varying the relative frequencies of said carriers without audio-frequency amplitude modulation of the carriers so that the actual frequency difference is in a predetermined audio frequency band, and radiating said carriers from separate antennae to a common receiving point.

5. A primary radio frequency oscillator of fixed frequency, another primary radio frequency oscillator of shiftable frequency, means to shift the frequency of said other oscillator without audio frequency carrier amplitude modulation and under control of signals to be transmitted so that the actual frequency difference between said oscillators equals the frequency of the signal to be transmitted, an amplifier for both of said oscillators, and a common radiating antenna fed from said amplifier.

6. In a radio transmission system of the character described, a pair of primary radio frequency oscillators, means to vary the frequencies of said oscillators without audio-frequency amplitude modulation thereof but under control of audio frequency signals so that the frequency difference between the oscillators equals the frequency of the signals to be transmitted, a common amplifier for both of said oscillators, and a common radiating antenna fed from said amplifier.

RICHARD A. HILFERTY.
